CLAIM

The ornamental design for an illuminating rod, as shown and described.

DESCRIPTION

FIG. 1 is a top and front perspective view of an illuminating rod showing my new design;

FIG. 2 is a top plan view thereof;

FIG. 3 is a front elevational view thereof, the rear elevational view, left side elevational view and right side elevational view being a mirror image;

FIG. 4 is a bottom plan view thereof;

FIG. 5 is a top, front and left side perspective view of a second embodiment of my new design;

FIG. 6 is a top plan view thereof;

FIG. 7 is a front elevational view thereof, the rear elevational view being a mirror image;

FIG. 8 is a left side elevational view thereof, the right side elevational view being a mirror image; and,

FIG. 9 is a bottom plan view thereof.
